UNITED STATES PATENT OFFICE.

ELBERT A. McSPADDEN, OF CRAWFORDSVILLE, INDIANA.

DAMPER SEAT.

1,407,210.

Specification of Letters Patent. Patented Feb. 21, 1922.

Application filed December 29, 1919. Serial No. 347,950.

To all whom it may concern:

Be it known that I, ELBERT A. McSPADDEN, a citizen of the United States, residing at Crawfordsville, in the county of Montgomery and State of Indiana, have invented a new and useful Damper Seat, of which the following is a specification.

This invention relates to a combined damper and flue cleaner, the primary object of 10 the invention being to provide a construction wherein the damper may be operated to remove soot from the flue in which the pipe supporting the damper, is supported.

Another object of the invention is to provide 15 a pipe section especially constructed to permit the same to be forced into a flue.

With the foregoing and other objects in view, which will appear as the description 20 proceeds, the invention resides in the combination and arrangement of parts and in the details of construction hereinafter described and claimed, it being understood that changes in the precise embodiment of the invention herein disclosed can be made with- 25 in the scope of what is claimed without departing from the spirit of the invention.

A practical embodiment of the invention is shown in the accompanying drawing, 30 wherein:—

Figure 1 is a sectional view through a flue and chimney, disclosing a damper seat and damper supported in the damper seat.

Figure 2 is an enlarged view in perspective of the damper seat;

Figure 3 is an enlarged fragmentary view in perspective of the damper.

Referring to the drawing by numerals of reference:—

A chimney is indicated at 1, and is provided 40 with a flue 1', to which the usual opening 1'' leads.

Within the opening 1'', and resting in the bottom of the flue 1', is placed the damper rest or seat, which consists of a short 45 cylindrical portion 2 adapted to fit within the opening 1'', and the integral, semi-cylindrical portion 3 which rests in the bottom of the flue, but it is to be understood that if more than one stove has communication 50 with a single flue, the portion 3 should be provided with an opening in the bottom thereof to permit the products of combustion to pass therethrough.

The end of a section of stove pipe 4 telescopes into the portion 2 of the damper seat, 55 and an elbow 5 is provided at the other end of the section of pipe 4. The elbow 5 is formed with an aperture 6 through which a rod 7 is slidable, the rod extending longitudinally of the section of pipe 4 and having 60 its outwardly projecting end bent to form an operating handle 8.

To the inner end of the rod 7 is secured the damper which consists of a disk 9, preferably having a slight portion cut away, as 65 at 9', and apertured centrally to receive the end of the rod 7, on which it is bound by a nut 10, which nut is threaded on the end of the rod.

As will be understood, the rod 7 may be 70 moved back and forth longitudinally to change the position of the damper 9, and so vary the draft of the chimney. When the damper is drawn to the position shown in dotted lines in Figure 1, soot is scraped 75 from the bottom of the flue and from the pipe section 4, and expelled through the elbow 5, thus keeping the entrance to the flue clean and assuring a proper draft.

Having thus described the invention, what 80 is claimed as new and sought by Letters Patent, is:—

In combination with a chimney having a flue and an opening in the flue, a damper seat consisting of a relatively short pipe 85 section having its outer extremity formed as a semicylindrical portion, said damper seat adapted to be positioned within the opening of a flue, the outer extremity of the damper seat lying flush with the front wall of the 90 flue, the inner end of the damper seat being open, a pipe having one end thereof positioned within the damper seat, a damper movable within the damper seat, said damper having a curved cut out portion, and 95 a rod for moving the damper.

In testimony that I claim the foregoing as my own, I have hereto affixed my signature in the presence of two witnesses.

ELBERT A. McSPADDEN.
